To all whom it may concern:

Be it known that I, Ida Lampel, a citizen of the United States of America, residing in New York city, in the Borough of Manhattan, county and State of New York, have invented a new, original, and ornamental Design for a Dress, of which the following is a specification, reference being had to the accompanying drawing, forming part thereof, wherein,

Figure 1 is a front view of a dress showing my new design.

The characteristic feature of my design resides in the combination on the dress as shown, of the skirt portion which extends upward to a point below the neckline where it is caught with the bodice portion with self loopings, as shown.

I claim:

The ornamental design for a dress, substantially as shown and described.
